LIGHTING FIXTURE LENS

Viktor Schreckengost, Cleveland, Ohio, assignor
to Holophane Company, Inc., New York, N. Y.,
a corporation of Delaware

Application April 24, 1953, Serial No. 24,651

Term of patent 14 years

(Cl. D48—16)

To all whom it may concern:

Be it known that I, Viktor Schreckengost, a citizen of the United States of America and a resident of Cleveland, in the county of Cuyahoga, in the State of Ohio, have invented a new, original, and ornamental Design for a Lighting Fixture Lens of which the following is a specification, reference being had to the accompanying drawings, forming a part thereof.

In the drawings:

Fig. 1 is a bottom perspective view of a lighting fixture lens showing my new design;

Fig. 2 is a bottom plan view thereof;

Fig. 3 is a top plan view;

Fig. 4 is a fragmentary cross-sectional view

to a larger scale taken on the line 4—4 of Fig. 3; and

Fig. 5 is a fragmentary cross-sectional view to a larger scale taken on the line 5—5 of Fig. 3.

I claim:

The ornamental design for a lighting fixture lens, as shown.

VIKTOR SCHRECKENGOST.
